UNITED STATES PATENT OFFICE.

JOHANN JAKOB KNECHT, OF SCHÖNAU, NEAR CHEMNITZ, GERMANY.

MACHINE FOR PUNCHING JACQUARD-CARDS FOR AUTOMATIC EMBROIDERY-MACHINES.

1,151,191.

Specification of Letters Patent. Patented Aug. 24, 1915.

Application filed November 22, 1912. Serial No. 732,868.

To all whom it may concern:

Be it known that I, JOHANN JAKOB KNECHT, a citizen of Switzerland, residing at Parsivalstrasse 1, Schönau, near Chemnitz, in the Kingdom of Saxony, Germany, have invented new and useful Improvements 5 in Machines for Punching Jacquard-Cards for Automatic Embroidery-Machines, of which the following is a specification.

10 The present invention relates to machines for punching jacquard cards for automatic embroidering machines, and particularly to card-punching machines wherein the movement of a point or stylus over the pattern 15 or design of the embroidery to be produced is adapted to set or adjust two movable perforated devices, such as rotatable drums or drum sectors formed with rows of perforations arranged according to a suitable 20 scheme. The adjustment of the drums is effected in known manner from two cross members which, through suitable intermediate mechanism, such as toothed racks, transmitting bands and the like, are connected thereto.

25 In one type of card-punching machine to which the present improvements are applicable, the drums or drum sectors after having been set in the described manner by 30 the displacement of the point or stylus, are moved toward each other, and actuate corresponding punches, whereby the required 35 perforations are produced upon an intermittently fed paper band or card. These perforations indicate the lengths of the co-ordinates of the points of the stitches, and are, as a rule, utilized for determining the horizontal and vertical displacement of the 40 work frame. The manner in which these cards are used in automatic embroidering 45 machines is well-known and does not require further description.

It may be mentioned that the perforations arranged upon the periphery of the drums 50 or other equivalent devices are arranged according to a certain scheme. For instance, the successive rows of perforations indicating the lengths of the coördinates of the points of stitches may progress in arithmetic- 55 cat order 1, 2, 3, 4, 5 . . .

The object of the present invention is to provide means whereby the length of a co-ordinate of a point of stitch will be correctly indicated upon the card to be punched, even 55 in the case where the member containing the

diagram of perforations is moved past the starting point during the setting operation. In the ordinary type of card-punching machines at present constructed, a setting movement of the drum which is more than 60 one revolution of the drum cannot be correctly recorded, as, after the completion of one revolution, the records would be merely repeated.

The invention is, therefore, particularly 65 important for all kinds of card-punching machines serving for producing jacquard cards for automatic embroidering machines in which the length of the coördinate of the point of the stitch is always measured 70 from a certain starting point.

Up to the present it has not been possible 75 to record the movement of the diagram of perforations when same had passed the starting point, that is to say, the motion of 80 the diagram of perforations could only be recorded within a certain limit which was determined by the length of the diagram of perforations. If, for instance, the whole 85 diagram is divided into 150 units, and, if it is desired to follow a stitch of the size 50 by a particularly large stitch of say the size 170, a card produced by the machines at present in use would indicate only a stitch 90 of the size 70. For although the diagram be moved from 50 to the terminal point 150 and from there to the point 70, no record 95 would appear on the card showing that the whole diagram was once developed and moved past the starting point. The card would indicate only that part of the movement which was performed after passing the starting point.

According to the present invention, the 100 punches for perforating the card are divided 95 into two groups. The punches of the one group are selected in the usual manner by the perforations of the diagram or selecting drum, which perforations are brought opposite the same by the movement of the 105 stylus or point, whereas the punches of the other group are brought into and held in the operative position until the punching operation proper has been performed by the movement of the drum or other equivalent 110 device beyond the starting point. It will thus be seen that even after the drum or other equivalent device containing the diagram of perforations has been completely moved by the whole amount of its length,

the perforations produced will indicate the correct length of the coördinate of the last point of the stitch, the rows of perforations produced upon the card corresponding exactly to the actual size of the stitch.

In order that the invention may be clearly understood reference is made to the accompanying drawings in which—

Figure 1 shows by way of example a known arrangement of card-punching machine to which the present invention may be applied. Fig. 2 illustrates the subject of the invention, namely the arrangement of two groups of punches and the means for operating the same. For the sake of clearness, only one diagram of perforations which is here in the shape of a cylindrical drum is shown. Figs. 3 and 4 show some detail parts of the actuating or controlling mechanism in various characteristic positions.

The movement of the point or stylus 1, which is in the usual manner moved forward and backward over the design in a manner corresponding to the desired production of stitches by the jacquard mechanism, actuates the cross-members 2, 2', which are connected by a suitable transmitting gear, such as, for instance a steel band 3, or 3', with the shaft 4, 4', of a drum 5, or 5' carrying a suitable diagram of perforations. Any movement of either of the cross members entails a corresponding rotary movement of the respective perforated drum. The perforated drums are thus set by the movement of the point in the usual manner, and, at each setting, a certain row of perforations which corresponds to the length of the coördinate of the point of the stitch to be produced, is brought opposite the punches 6, or 6'. The punches are slidably mounted in suitable guides between the two perforated drums. After the drums have been set they are moved toward each other and toward the punches whereby those punches which are opposite perforations of the drum are rendered inoperative, while other punches which are situate opposite solid portions of the drum are actuated and driven into the card band 7 which is fed after each operation.

At the beginning of the operation, a certain group of perforations of the drum which has a certain value, such as, for instance, the value 0 or any other value, is situated opposite the punches. This position of the drum may be considered as the starting point. When the drums are set either in the one or in the other direction, certain other groups of perforations are brought opposite the punches. Should the drum receive a movement of such magnitude as to cause that row of perforations which was used as the starting point, to pass the punches a second time, this movement

cannot be properly recorded upon the card, and the record produced upon the card is therefore, from this point wrong.

According to the present invention, whenever a certain group of perforations, for instance, that corresponding to the stitch size zero, is moved for the second time past the starting point, one or more punches of a second group of punches 6^w (Fig. 2) is made ready for operation and kept in this position so that it may afterward be brought into operation simultaneously with the other punches 6. For the sake of clearness, only a few of the ordinary punches 6 are shown in the drawings. In this manner, the complete revolutions of the drum are recorded upon the card, and it is insured that the subsequent perforations are made correctly.

Those portions of the periphery of the drum which are opposite the second group of punches 6^w are provided along the whole circumference with perforations so that the punches 6^w cannot at any position of the drum be accidentally brought into operation and produce perforations in the card. Only when the drum 5 has been moved beyond the starting point of the diagram is one of the punches 6^w rendered operative and maintained in the operative position by additional means, for instance, by the aid of a pressure-piece 8 which is brought between the punch and the perforation of the drum.

The movement of the member which renders the punch operative is, in the construction shown, obtained by forming the face of the drum with a number, for instance five, of grooves 9, which coöperate with feelers 10, which in turn are connected with the aforesaid member 8 by a lever mechanism 11, 12. The grooves 9 are connected at the critical point by cam portions 13, so that, whenever the critical point is passed, the feeler 10 receives a movement which is transmitted to the member 8.

In order to illustrate the working of the improved apparatus, the same example given in connection with the known construction of card-punching machines will be taken. The punching drum after being set actuates in the usual manner the punches 6 of the first group in such a manner as to produce upon the card perforations corresponding to the stitch size 70. At the same time, however, as the drum has been moved beyond its terminal point 150, the additional apparatus forming the subject of the invention is brought into operation and one or more of the additional punches 6^w is or are made ready to be subsequently operated. During the punching operation proper, these punches 6^w are operated together with the punches of the group 6 and a record is produced upon the card which shows clearly that the drum has not been moved from 50 to 70, but has been moved from 50

to 150 and then from 150 (or zero) again to 70,—the length of the coördinate of the last point of the stitch 170 having a value of 220, that is 50 plus 170.

It will be noted that the punches of that group which serves for indicating the movement of the drum or equivalent part past the starting point, are made ready for the subsequent punching operation before the punches of the other group are controlled or selected, but they are brought into operation at the same time as the punches of the other group. They are also returned to their initial position after the 15 punching operation proper in a similar manner to the punches of the other group.

Owing to the particular form of the member 8, a single feeler mechanism 10, 11, 12 may be used for operating either of two 20 punches of the group 6^w according to whether the drum has been moved past the starting point in the one or in the other direction. As will be seen from Figs. 2 and 4, the member 8 is made in the shape of a hook. When the drum is rotated in the 25 forward direction beyond the critical point, the member 8 covers the left punch 6^w (Fig. 4, b) while during the backward rotation of the drum, the right punch 6^w will be 30 covered (Fig. 4, c).

After the feeler 10 has been moved by the cam portion 13 in the one or the other direction according to the direction of rotation of the drum, and has caused the jac- 35 quard card to receive an additional perforation, it is returned to its normal position within the concentric portion of a groove 9 by the following mechanism:

The tail end 11' of the lever 11 extends 40 through a cross-shaped slot 14 of an arm 16 of a lever 15. The other arm of the lever 15 engages into one of two slides 17 which, at each operation of the punching machine, are operated by the cam 20 through the 45 intermediate levers 19, 18. When the feeler 10 is moved, which movement as above stated is transmitted by the parts 11, 12 to the hook 8, the tail end 11' of the lever 11 passes from the normal position shown in 50 Fig. 3, a, say into the position shown in Fig. 3, b. Upon the two slides 17 performing their movement toward each other, the lever 15 is first turned upon the pivot 22 whereby the lever 11, which is hinged to the tail 55 end of the lever 12 is moved into the position shown in Fig. 3, c, and the feeler 10 is withdrawn from the groove. In the meantime, one of the two slides 17 has approached the lever 12 which extends between the two slides, and has moved the 60 lever 12 so as to return the tail end 11' to its middle position (Fig. 3, d). When the lever 11 has reached its middle position in the vertical direction it is moved by the 65 spring toward the face of the drum, where-

by the feeler 10 is again caused to engage into the concentric portion of the groove 9. The lever 15 is then returned to its initial position so that all parts resume their normal positions as shown in Fig. 3, e.

I claim:

1. A card-punching machine for automatic embroidering machines comprising means for punching the card to mark the coördinates of the points of various sizes of 75 stitches up to a predetermined length of the coördinate of a point of stitch, and auxiliary and automatic means for punching the card for stitches when the coördinate of a point of stitch is of greater length than said predetermined length, substantially as described.

2. A card-punching machine for automatic embroidering machines comprising a group of punches, means for actuating said punches to perforate the card to mark the 85 coördinates of the points of stitches up to a predetermined length of a coördinate of a point of stitch, a second group of punches, and automatic means for actuating both groups of punches, to perforate the card to 90 mark the coördinates of the points of stitches when said coördinates are over said predetermined length, substantially as described.

3. A card-punching machine for automatic embroidering machines comprising 95 a rotary member containing a diagram of perforations, punching means actuated by said rotary member to perforate the card to mark the coördinates of the points of stitches up to a predetermined length of a coördinate 100 of a point of stitch, and auxiliary punching means actuated automatically from said rotary member in conjunction with first said punching means to perforate the card to mark the coördinates of stitches when said 105 coördinates are over said predetermined length, substantially as described.

4. A card-punching machine for automatic embroidering machines comprising a 110 rotary perforated drum formed with a diagram of perforations, means actuated by said device to punch the card to indicate the coördinates of the points of stitches during the first revolution of the drum, in combination with auxiliary means for punching 115 the cards to indicate the correct coördinates of the points of stitches when the said drum has been rotated more than one revolution; substantially as described.

5. A card-punching machine for automatic embroidering machines, comprising a 120 rotatable drum formed with a diagram of perforations, means actuated by said device to punch the card to indicate the points of stitch coördinates of normal length, in combination with automatically controlled means for punching the card to indicate the points of stitch coördinates of abnormal length when the said drum is rotated more than 125 one revolution; substantially as described. 130

6. A card-punching machine for automatic embroidering machines comprising a plurality of rotatable drums each having a predetermined arrangement of perforations, a plurality of groups of punches actuated by said drums to punch the card to indicate the points of stitch coördinates of normal length, in combination with other groups of punches for punching the card to 5 indicate the points of stitch coördinates of abnormal length when the said drums are rotated more than one revolution; substantially as described.
7. A card-punching machine for automatic embroidering machines comprising a 10 rotatable drum having a predetermined arrangement of perforations, a plurality of punches arranged to be actuated by said drum to punch the card to indicate the 15 points of stitch coördinates of normal length, a second set of punches for punching the card simultaneously with the first mentioned punches to indicate the points of stitch coördinates of abnormal length when 20 the said drum is rotated more than one revolution, and means for controlling the second set of punches; substantially as described.
8. A card-punching machine for automatic embroidering machines comprising a 25 rotatable drum having a predetermined arrangement of perforations, a plurality of punches actuated by said drum to punch the card, a second group of punches, and automatic means for controlling and actuating the second group of punches after the 30 drum has been rotated more than one revolution; substantially as described.
9. A card-punching machine for automatic embroidering machines, comprising a 35 rotatable drum formed with a diagram of perforations, a plurality of punches actuated from said drum to punch the card, in combination with a second group of punches, a hook-shaped pressure-piece, and 40 means for actuating said pressure-piece to render and maintain one of the second group of punches in operative position after the drum has been rotated more than one revolution.
10. A card-punching machine for automatic embroidering machines, comprising a 45 rotatable drum formed with a diagram of perforations, a plurality of punches actuated from said drum to punch the card, in combination with a second group of punches, a pressure-piece, grooves in the 50 face of the drum, and means actuated from said grooves to cause the said pressure-piece to render and maintain one of said second group of punches in operative position after the drum has been rotated more than one revolution.
11. A card-punching machine for automatic embroidering machines comprising a 55 rotatable drum formed with a diagram of 60 perforations, a plurality of punches actuated from said drum to punch the card, in combination with a second group of punches, a pressure-piece, grooves in the face of the drum, and means for controlling and selecting the second group of punches before the first group, and means for simultaneously operating said punches to punch the card.
- perforations, a plurality of punches actuated from said drum to punch the card, in combination with a second group of punches, a pressure-piece, cams on said drum, and means operated by said cams to cause the said pressure-piece to render and maintain one of the second group of punches in operative position after the drum has been rotated more than one revolution.
12. A card-punching machine for automatic embroidering machines, comprising a 70 rotatable drum formed with a diagram of perforations, a plurality of punches actuated from said drum to punch said card, in combination with a second group of 75 punches, a pressure-piece, grooves in the face of said drum, cam portions in said grooves, feelers in said grooves actuated by the cam portions, and levers connecting said feelers to said pressure-piece to cause same 80 to render and maintain one of the second group of punches in operative position after the drum has been rotated more than one revolution.
13. A card-punching machine for automatic embroidering machines, comprising a 85 rotatable drum formed with a diagram of perforations, a plurality of punches actuated from said drum to punch said card, in combination with a second group of 90 punches, a pressure piece, grooves in the face of said drums, cam portions in said grooves, a spring actuated arm, feelers mounted on said arm and arranged to work in said grooves and a lever connecting said 95 spring-arm to said pressure-piece to cause same to render and maintain one of the second group of punches in operative position after the drum has been rotated more than one revolution.
14. A card-punching machine for automatic embroidering machines, comprising a 100 rotatable drum formed with a diagram of perforations, a plurality of punches actuated from said drum to punch said card, in combination with a second group of 105 punches, a pressure-piece, grooves in the face of said drum, cam portions in said grooves, a spring-actuated arm, a cross-shaped slot, a tail piece extending into said 110 cross-shaped slot, feelers mounted on said arm and arranged to work in said grooves and a lever connecting said spring arm to said pressure-piece to cause same to operate one of said second group of punches after 115 one revolution of the drum.
15. A card-punching machine for 120 embroidering machines, comprising a rotatable drum formed with a diagram of perforations, a plurality of punches set from said 125 drum, in combination with a second plurality of punches, means for controlling and selecting the second group of punches before the first group, and means for simultaneously operating said punches to punch the card.

16. A card-punching machine for embroidery machines, comprising a rotatable drum formed with a diagram of perforations, a plurality of punches set from said drum, in combination with a second plurality of punches, a pressure-piece, grooves in the face of said drum, feelers in said grooves, means for connecting said feelers to said pressure-piece, means for removing 5 said feelers from said grooves and means for returning said feelers to said grooves.

17. A card-punching machine for embroidery machines comprising a rotatable drum formed with a diagram of perforations, a group of punches actuated from said drum, in combination with a second group of punches, a pressure-piece, grooves in the face of said drum, cam portions in said grooves, feelers in said grooves, levers connecting said feelers to said pressure-piece, two movable slides, and a lever connecting 10 said slides to said spring actuated arm.

18. A card-punching machine for embroidery machines comprising a rotatable drum formed with a diagram of perforations, a group of punches actuated from said drum, in combination with a second group of punches, a pressure-piece, grooves in the 15

face of said drum, cam portions in said grooves, feelers in said grooves, levers connecting said feelers to said pressure-piece, two movable slides, means for actuating said slides simultaneously to cause said feelers to return to working position. 20

19. A card-punching machine for embroidery machines comprising a rotatable drum formed with a diagram of perforations, a group of punches actuated from said drum, in combination with a second group of punches, a pressure-piece, grooves in the 25 face of said drum, cam portions in said grooves, a spring-actuated drum, feelers mounted on said arm and arranged to work in said grooves, a lever connecting said arm to said pressure-piece, two movable slides, a 30 lever connecting said slides to said spring mounted arm, and means for simultaneously moving said slides.

In testimony whereof I have signed my name to this specification in the presence of 35 two subscribing witnesses.

JOHANN JAKOB KNECHT.
